Primary Examiner — Elizabeth Albert(74) *Attorney, Agent, or Firm* — Wolf, Greenfield & Sacks, P.C.; Randy J. Pritzker(57) **CLAIM**

The ornamental design for pen, as shown and described.

DESCRIPTION

FIG. 1 is a side, top, perspective view of a pen showing our new design;

FIG. 2 is a left side view thereof, the right side view being a mirror image of the left side view;

FIG. 3 is a top view thereof;

FIG. 4 is a bottom view thereof;

FIG. 5 is a front view thereof;

FIG. 6 is a rear view thereof;

FIG. 7 is a side, top perspective view of the pen shown without the cap for convenience;

FIG. 8 is a front view thereof;

FIG. 9 is a rear view thereof;

FIG. 10 is a perspective view of the cap shown without the pen for convenience; and,

FIG. 11 is a rear view thereof.

The broken lines showing the clip in FIGS. 1-3, 5 and 6; part of the pen in FIGS. 7 and 8, 3 and the inside of the cap and the clip in FIGS. 10 and 11 are included for the purpose of showing portions that form no part of the claimed design.
